(57) **CLAIM**

The ornamental design for commode chair, as shown and described.

DESCRIPTION

FIG. 1 is a front perspective view of the commode chair embodying the design;

FIG. 2 is a front view of the commode chair;

FIG. 3 is a back view of the commode chair;

FIG. 4 is a left side elevation of the commode chair;

FIG. 5 is a right side elevation of the commode chair;

FIG. 6 is a top view of the commode chair; and,

FIG. 7 is a bottom view of the commode chair.

The broken lines showing of commode bowl and toilet paper roll is for illustrative purposes only and forms no part of the claimed design.

1 Claim, 6 Drawing Sheets
